UNITED STATES PATENT OFFICE.

MARSHMAN W. HAZEN, OF NEW YORK, N. Y., ASSIGNOR TO CORONA TYPEWRITER COMPANY, INCORPORATED, A CORPORATION OF NEW YORK.

FEED MECHANISM.

1,121,095.

Specification of Letters Patent. Patented Dec. 15, 1914.

Original application filed June 23, 1908, Serial No. 439,967. Divided and application filed June 3, 1909, Serial No. 499,873. Renewed October 8, 1914. Serial No. 865,771.

To all whom it may concern:

Be it known that I, MARSHMAN W. HAZEN, a citizen of the United States, and a resident of New York, county and State of New York, have invented certain new and useful Improvements in Feed Mechanisms, of which the following is a full, clear, and exact description.

This invention relates to the feed mechanism of typewriting machines, and is a division of my pending application Sr. No. 439,967, filed June 23, 1908.

The primary object of the invention is to provide a simple and efficient feed mechanism for the carriage of a typewriting machine which is so constructed that the carriage may be moved to different positions to permit the type-heads to have a plurality of characters thereon and the carriage operated for letter spacing no matter in what position the said carriage may be placed.

Another object of the invention is to provide simple and efficient feed mechanism for a machine in which the platen, carriage and escapement mechanism may be moved vertically and the parts so arranged that they may be folded over into overhanging relation to the keyboard to cause the machine to occupy less space than when in use, and in which a part of the feed mechanism is adapted to be moved vertically with the carriage and so connected to the key-levers as to be readily operated thereby.

A further object of the invention is to provide a machine in which the parts are very strong, light and readily accessible and easily repaired.

With these and other objects in view, the invention will be hereinafter more particularly described with reference to the accompanying drawings, which form a part of this specification, and will then be pointed out in the claims at the end of the description.

In the drawings, Figure 1 is a longitudinal section, partly in elevation, of one form of machine embodying my invention. Fig.

2 is a rear elevation. Fig. 3 is an inverted plan of the carriage and part of the escapement and feed mechanism removed from the machine. Fig. 4 is an enlarged vertical section of a part of the escapement mechanism; and Fig. 5 is a fragmentary view of the upper part of the machine showing the parts on which one of the carriage guide rails run.

The frame 10 on which the several parts are mounted may be of any suitable construction and may consist of side-pieces or members 11, a rear piece or member 12 integral with the side-pieces and with an intermediate transverse bar or plate 13 serving to brace the side members 11 substantially centrally thereof, all of which may be of aluminum for the purpose of making the same light, or of sheet metal or other material. Extending transversely of the frame at the front thereof is a transverse bar 14 which may be covered by a strip of felt 15 or sound-deadening material and which serves to limit the downward movement of the key-levers 16.

On the outer end of the levers 16 are the keys or finger-pieces 17 having the usual characters as in the ordinary form of machine. The key-levers 16 are pivotally held upon a plurality of bars or rods 18 arranged transversely of the machine and in parallel relations so that said bars may be held and arranged close to each other. To the inner end of each lever 16, as at 19, is held a link 20, and said link is connected to a type-bar 21 which is pivoted at 22 to a bracket 23 arranged on the rear side or member 12 of the machine frame.

At the forward end of each type-bar 21 is arranged a type-head 24 having a plurality of characters 25, 26 and 27 thereon, one to indicate the lower case characters, the intermediate the upper case characters, and the outer or 27 indicating the figures, the type-bars and brackets 23 being arranged in a circular or segmental form. Each key-lever when depressed is forced against the

tension of a spring 28. Each spring is fastened at one end to the key-lever and the other end to a rod 29 so that as each key-lever is depressed it will force the type-bar upward into printing position, and as soon as released will return the same to its normal position, the said type-bars normally resting upon a felt strip 30 arranged upon a bar or plate 31 extending transversely of the machine.

The platen 32 for holding the work may be of the usual form and is mounted to rotate between side brackets 33 of the platen frame forming a part of a movable carriage 34.

The carriage 34 is provided with a rail 35 which is adapted to move in a slot 36 in the upper surface of a bar 37 forming a part of the carriage bed 38 and at the rear of said bed, while the front of the carriage is provided with a rail or guide 39 which is adapted to rest at its lower edge on a plurality of buttons or engaging devices 40 arranged along the upper face or surface of the carriage bed in such a way as to reduce the friction of the carriage to a minimum, and at the same time hold the carriage in its proper relation to other parts of the machine. The carriage is normally forced in one direction by means of a spring arranged within a drum 42. The drum is located under the carriage bed, and to said drum a flexible connection, as a cord 42^a, is held at one end, and at its other is fastened to a pendent arm 43 which is adjustably held by means of a screw 44 to a transversely extending bar 45 so that when the carriage is released, as will be presently described, by the movement of one of the key-levers while printing, the spring-operated drum, by means of an escapement mechanism, will force the carriage a distance equal to one space as is usual in typewriting machines. It will be seen that the spring will have greater force for pulling the carriage in starting a line because it is wound up than it has when near the end of the line, and to compensate for this variation in the tension of the spring instead of providing simply a plurality of buttons 40 to extend throughout the entire carriage bed 38 at intervals, I may arrange at one end of the machine one or more rolls 46, Fig. 5, which will engage the rail or guide 39 at one end thereof when the same has been moved a certain distance by the connection 42^a, the spring thus causing the carriage to move more readily at one end than at the other and thereby compensating for the uneven pull thereon by the spring.

The arm 43 is supported by a block 47 which is adjustable along the rod or bar 45 at one end of the machine.

At or near the other end of the machine and adjustably held by means of a screw 48 or otherwise is a block 49 from which, as

well as the block 47, projects a guide or work-retaining finger 50 which is adjustable along the platen to adapt different sizes of work to be held thereon as usual. Between the adjustable fingers 50 may be arranged a guide plate or work table 51 which may be supported by the bar 45 and is adapted to extend under and toward the front of the platen to guide the work, and journaled between the lugs 52 on the work table 51 is a friction roll 53 for causing the work to be moved as the platen is rotated.

As an escapement mechanism and means for operating the same I provide the carriage 34 with a rack-bar 55 under the same, and this rack-bar is provided with the usual ratchet-shaped teeth which are adapted to be engaged by the escapement pawls or dogs 56 and 57, Figs. 1, 3 and 4, one of which, as 56, is fixed and the other, as 57, is movable. These dogs permit the carriage to move the distance of a single tooth in the usual way when the dogs are moved laterally transversely of the rack bar. The dogs 56 and 57 are substantially triangular and are carried by a horizontally movable arm 58. This arm is pivoted at 59 to the carriage bed under the same and has its opposite end or head, as 60, guided in a slot 61 of a bracket 62. The dogs carried by the arm 59 move laterally of the rack-bar and allow the carriage to escape one tooth at a time, and said dogs swing in an arc of a circle across the face of the rack-bar in the same plane as said bar instead of in a direct line. This action causes the dogs to engage the rack teeth at one point instead of along the entire surface and thereby materially reduces the wear and friction thereof. A spring, as 63, is arranged on the carriage bed, Fig. 4, and has one end passing through the fixed dog 56 and is so arranged that it will only force the dog and the arm in one direction.

A stop 64 projects at an angle from the arm 58, and said stop is adapted to engage a projecting part or tooth 65 of the movable dog 57, in order to limit its movement in one direction. The loose dog is normally yieldingly held against movement in one direction by a spring 66, and in the opposite direction by a spring 67, though instead of the two springs a single spring may be employed if desired. These springs 66 are flat metal strips arranged one over the other and the ends of said springs are adapted to engage the lower edge of the loose dog on opposite sides of its pivot.

To operate the escapement no matter what position the carriage may be in, a movable bar 68 of the escapement-operating frame is arranged transversely of the machine and a collar or projecting part 69 is provided thereon which is adapted to engage the head 60 of the arm or dog carrier 58 so as to move the escapement dogs against the action of

the spring 63. This bar is held in the upper end of the arms or levers 70 of the escapement frame, which arms are pivoted on opposite sides of the machine to a transversely-extending rod or bar 71, and in the upper end of each of said arms 70 is a vertical slot 72.

A bell-crank or angular lever 73 is pivoted at 74 to a part of the machine frame on each side thereof, and has one end, as by a screw 75, guided in the slot 72 of the arm 70 and its other end connected by a link or rod 76 to a universal bar 77. This universal bar 77 extends transversely of the machine over each key-lever so that as each key-lever is depressed, it will raise the bar 77 and move the bell-crank levers 73 on their pivots 74, and by means of the shoulder screw 75 in the slot 72 of the arms 70 will throw the escapement-moving bar 68 outward and thereby move the escapement arm 58 carrying the dogs against the tension of the spring 63.

The arms 70, Fig. 1, may be forced inward by the flat upwardly extending springs 77^a which are held at one end to the part 12 of the frame and engage the arms 70 at their free ends. An adjusting screw 77^b is adapted to engage each spring 77^a to vary the pressure of the springs against the arms 70, and by means of the bell-crank levers 78 and links 76, the universal bar 77 will be forced against the action of the key-levers with any desired pressure. This action of the spring 77^a not only serves to permit the force required to operate the type-bars to be increased, but they serve to restore the type-bars and key-levers to their normal position, and if desired the springs 28 for each key-lever may be dispensed with.

The machine is provided with means for raising the entire carriage bed and mechanisms carried thereby to different heights, to position the platen 32 properly with respect to the upper case characters and the figures on the type-heads so that the same will properly strike the work sheet held by the platen, and means are also provided whereby the platen and the mechanism movable therewith may be locked in its different positions.

The cap-shift lever 78 has its inner end fixed to a transverse rod 79 which is pivoted to the machine frame and said lever is extended inward to the rod 80 so that the two latter rods may be moved in unison.

An arm 81 projects from the rod 79 to which one end of the rod 80 is fixed. This arm 81 has a pivotal connection with the rod 71 at its inner end, and said rod at its ends is held to slides or rods not shown, each of which is movable in a bearing located at the upper rear corner of the machine frame. The bearings are each held to the rear part of the machine frame so that as the lever 78 is depressed, the bars 71 will

raise the slides and lift the platen, carriage bed, mechanism carried thereby, and the escapement frame with the transverse bar 68 to adapt the escapement mechanism to be operated no matter in what vertical shifted position the platen may be in. There is also a figure shift lever and other features which are not shown, but as the platen shift mechanism forms no part of the present invention it was thought unnecessary to further describe or show the same.

While I show and describe features of a typewriting machine other than those of the present invention, such features are not claimed herein as they form a part of my application hereinbefore referred to or of other and copending applications.

From the foregoing it will be seen that simple and efficient feed mechanism for the carriage is provided; that said mechanism will positively feed and hold the carriage at each movement so as to obtain proper letter spacing; that said feed and escapement mechanism will operate the carriage no matter what position the same may be placed in; that simple means is provided whereby a minimum amount of wear takes place between the escapement elements and the carriage; and that said feed mechanism is so constructed that a part of the same may be mounted upon the carriage which is adapted to be folded over above the keyboard of the machine.

Having thus described my invention, I claim as new and desire to secure by Letters Patent:—

1. In a typewriting machine, the combination with a support, of a carriage bed held to said support, a carriage held to move along the carriage bed, a rack movable with the carriage, an arm pivotally held to the carriage bed under the same, two dogs carried by the arm, one fixed thereto, and the other pivotally held to the arm, said arm being arranged to move horizontally and transversely of the carriage, means yieldingly holding the pivoted dog in one position, an angular fixed stop carried by the arm adapted to engage a part of the pivoted dog, a spring held to the bed and engaging one of the dogs tending normally to force the arm in one direction, said arm having an enlarged projecting head, and means operated by the key-levers for operating the arm and dogs to permit letter-spacing.

2. In a typewriting machine, the combination with a support, of a carriage bed held to said support, a carriage held to move along the carriage bed, a rack movable with the carriage, an arm pivotally held to the carriage bed under the same, two substantially triangular dogs carried by the arm, one fixed thereto, and the other pivotally held to the arm, said arm being arranged to move horizontally and transversely of

- the carriage, two springs acting on the pivoted dog at different points, an angular fixed stop carried by the arm adapted to engage a part of the pivoted dog, a spring held to the bed and normally forcing the arm in one direction, and means operated by the key-levers for operating the arm and pawls to permit letter-spacing.
3. In a typewriting machine, the combination with a support, of a carriage bed held to said support, a carriage held to move along the carriage bed, a rack movable with the carriage, an arm pivotally held to the carriage bed under the same, two dogs carried by the arm, one fixed thereto, and the other pivotally held to the arm, two springs of relatively different lengths engaging the pivoted dog at different points, and means for operating the arm to permit letter-spacing.
4. In a typewriting machine, the combination with a support, of a carriage bed held to said support, a carriage held to move along the carriage bed, a rack movable with the carriage, an arm pivotally held to the carriage bed, two dogs carried by the arm, one fixed thereto, and the other pivotally held to the arm, said arm being arranged to move horizontally and transversely of the carriage, two springs of different lengths arranged one above the other and engaging the pivoted dog at different points with respect to its pivot, and means for operating the arm.
5. In a typewriting machine, the combination with a support, of a carriage bed held to said support, a carriage held to move along the carriage bed, a rack movable with the carriage, an arm pivotally held to the carriage bed, two substantially triangular dogs carried by the arm, one fixed thereto, and the other having a tooth and pivotally held to the arm, said arm being arranged to move horizontally and transversely of the carriage, springs yieldingly holding the pivoted dog in one position, an angular fixed stop carried by the arm adapted to engage the tooth of the pivoted dog, a spring secured to the bed and tending normally to force the arm in one direction, and means operated by the key-levers for moving the arm and dogs to permit letter-spacing.
6. In a typewriting machine, the combination of a support, a carriage bed held to said support, a carriage held to move along the carriage bed, a rack movable with the carriage, an arm pivotally held to the carriage bed under the same, two dogs carried by the arm, one fixed thereto, and the other pivotally held to the arm, said arm being arranged to move horizontally and transversely of the carriage, a spring yieldingly holding the pivoted dog in one position, a stop projecting from the arm and adapted to engage a part of the pivoted dog to limit its movement in one direction, and means for operating the arm for letter-spacing.
7. In a typewriting machine, the combination of a support, a carriage bed held to said support, a carriage adapted to move along the bed, a rack movable with the carriage, an arm pivotally held to the bed under the same, two dogs carried by the arm, one fixed thereto and the other pivotally held to the arm, and an angularly arranged stop projecting from the arm and adapted to engage a part of the pivoted dog to limit its movement in one direction, and means for operating the arm.
8. In a typewriting machine, the combination of a support, a carriage bed held to said support, a carriage adapted to move along the bed, a rack movable with the carriage, an arm pivotally held to the bed, two dogs carried by the arm, one fixed thereto and the other pivotally held to the arm, two springs acting upon the pivoted dog, and means for operating the arm.
9. In a typewriting machine, the combination of a support, a carriage bed held to said support, a carriage adapted to move along the bed, a rack movable with the carriage, an arm pivotally held to the bed, two dogs carried by the arm, one fixed thereto and the other pivotally held to the arm, the fixed dog being substantially triangular and the pivoted dog having a cut away part to form a shoulder, and a stop projecting from the arm and adapted to engage the shoulder of the pivoted dog to limit its movement in one direction, and means for operating the arm.
10. In a typewriting machine, the combination of a support, a carriage bed held to said support, a carriage adapted to move along the bed, a rack movable with the carriage, an arm pivotally held to the bed, two dogs carried by the arm, one fixed thereto and the other pivotally held to the arm, the pivoted dog having a cut away part to form a shoulder, an angularly arranged stop projecting from the arm and adapted to engage the shoulder of the pivoted dog to limit its movement in one direction, means for yieldingly holding the pivoted dog in a certain position relatively to the fixed dog, and means for operating the arm.
11. In a typewriting machine, the combination with a support, of a carriage mounted on said support, spring-actuated means tending normally to force the carriage in one direction, means for permitting the carriage to have a step-by-step movement, together with means for varying the friction between the carriage and bed to compensate for the varying tension of the spring-actuated means.

12. In a typewriting machine, the combination with a support, of a carriage mounted on said support, spring-actuated means tending normally to force the carriage in one direction, means for permitting the carriage to have a step-by-step movement, together with a plurality of fixed and movable devices supporting the carriages for varying the friction between the carriage and the

bed to compensate for the varying tension of the spring-actuated means.

This specification signed and witnessed this 29th day of May A. D. 1909.
